DESIGN FOR A SOUND REPRODUCER OR THE LIKE

Kyle M. Drollingen, Wichita Falls, Tex., assignor
to Herbert W. Carpenter, Wichita Falls, Tex.

Application February 9, 1942, Serial No. 105,727

Term of patent 3½ years

To all whom it may concern:

Be it known that I, Kyle M. Drollingen, a citizen of the United States, residing at Wichita Falls, in the county of Wichita and State of Texas, have invented a new, original, and ornamental Design for Sound Reproducer or the like, of which the following is a specification, reference being had to the accompanying drawing, forming part hereof, in which:

Fig. 1 is a side elevation of a sound reproducer or the like embodying my new design;

Fig. 2 is a bottom plan view thereof; and

Fig. 3 is a partial vertical sectional view taken through the center thereof.

I claim:

The ornamental design for a sound reproducer or the like, substantially as shown.

KYLE M. DROLLINGER.
